E. J. BANKER & J. B. STRONG.
RAIL TIE PLATE CLAMP.
APPLICATION FILED APR. 23, 1914.

1,108,881.

Patented Sept. 1, 1914.

Fig. 1.

UNITED STATES PATENT OFFICE.

EDWARD JAMES BANKER, OF SLOATSBURG, AND JAMES BOORMAN STRONG, OF HILLBURN, NEW YORK, ASSIGNORS TO RAMAPO IRON WORKS, OF HILLBURN, NEW YORK, A CORPORATION OF NEW YORK.

RAIL-TIE-PLATE CLAMP.

1,108,881.

Specification of Letters Patent. Patented Sept. 1, 1914.

Application filed April 23, 1914. Serial No. 833,859.

To all whom it may concern:

Be it known that we, EDWARD JAMES BANKER, a citizen of the United States, residing at Sloatsburg, in the county of Rockland, in the State of New York, and JAMES BOORMAN STRONG, residing at Hillburn, in the county of Rockland and State of New York, have invented certain new and useful Improvements in Rail-Tie-Plate Clamps, of which the following is a specification.

The invention relates particularly to means for securing a track and guard rail in adjusted position on a tie plate, and the invention consists in the new and novel features of construction and combinations of parts hereinafter set forth and claimed.

One of the principal objects of the invention is to provide a construction which permits quick and accurate adjustment both of the track and the guard rail, together with means for holding the same in their adjusted positions.

The various other objects of the invention will be more fully set forth in the following description of a rail tie plate clamp embodying our invention illustrated in the accompanying drawings, in which—

Figure 1 is an end view of a rail tie plate clamp showing the rails in position thereon. Fig. 2 is a plan view of the rail tie plate. Fig. 3 is a detail view showing the construction of the wedge plate and washer.

The track rails, such as the main rail 1 and the guard rail 2 are mounted upon the tie plate 3, which is provided with a ledge or shoulder 4 preferably formed integral therewith and against which the main rail abuts. The track rail and the guard rail are spaced at a suitable distance by a clip block 5 preferably comprising two parts 5 and 6 movable with relation to each other, each having a flange 7 resting upon the base of the adjacent track rail. One of said parts, as 5 is secured in fixed relation to the tie plate 4 and to the adjacent track rail by a lag screw 8 or other suitable means, and is also provided with a lip or flange 9 adapted to seat in a pocket 10 formed in the other part 6 of the clip whereby said part is normally held 50 against vertical movement.

If desired, the base of one or both of the track rails may be cut away to form a

squared shoulder against which the clip may abut, as shown by the guard rail illustrated in Fig. 1.

The tie plate is provided opposite the ledge or shoulder 4 with a solid shoulder 12, preferably upset from the tie plate and provided with a diagonal face 13. A wedge plate 14 is arranged between this shoulder 12 and the base of the guard rail. The wedge plate has a roughened top surface comprising wedge shaped teeth 15 and is also provided with a slot 16 diagonally arranged parallel to the diagonal edge of the plate. 60 The wedge plate may be provided with a lip or flange overlapping the adjacent edge of the track rail or brace block as the case may be.

The wedge plate is held in adjusted position by interlocking means comprising a bolt, screw or lug 17 which passes through the slot 16 and is secured in relatively fixed position with respect to the tie plate. Preferably the wedge plate is held by a bolt having an oval or elongated head 18 that engages in a corresponding recess or socket 19 provided in the bottom of the tie plate. This socket is so placed and formed that it will prevent the bolt from turning, but will permit a very slight tilting or adjusting movement thereof in the slot 16. A washer 20 is mounted on this bolt that has a roughened or toothed bottom surface comprising teeth 21 adapted to interlock with the corresponding teeth on the wedge plate. The bolt hole 23 through the washer is slightly larger than the bolt to allow slight play and permit the teeth on the bottom of the washer to engage with the teeth on the wedge plate in every position thereof. Preferably the washer overlaps the joint between the edge of the wedge plate and the tie plate. After the washer has been brought into place, it is forced into firm engagement with the wedge plate by suitable means as a nut 24. A locking nut 25 may also be used, if desired.

The device is assembled by placing the main rail and guard rail in position and then adjusting the wedge plate between the base of the guard rail and the shoulder 12 until all of the parts of the construction are firmly wedged into place. The washer 20 is then seated on the plate by being moved as

far as possible in a direction contrary to the wedging movement of the plate and the nut 24 is tightened until the wedge plate and the washer are firmly locked under considerable pressure. In case only the upper portions of the teeth engage, the wedging faces of the teeth will cause a certain amount of pull on the plate in the direction of its wedging movement and consequently, a certain amount of lost motion between the parts will be automatically taken up as the teeth gradually work together. In order to release the guard rail, the washer is first disengaged and the wedge plate driven lengthwise out of place, permitting the guard rail to be moved and access to be had to the clip and the main rail. In case it should be desired, for any reason, to vary the distance between the main rail and the guard rail, one of the parts of the clip is replaced by a corresponding part of greater thickness. This may easily be accomplished by loosening the lag screw and lifting up the casting thereon so as to permit the other part of the clip to be removed, without entirely removing the lag screw.

The slight play of the locking washer with respect to the bolt permits engagement between the teeth on the washer and the teeth on the wedge plate in every position of the latter and permits a certain amount of automatic adjustment of the parts that increases rather than diminishes pressure exerted on the track rail to hold the same in place.

It is obvious that a brace block can be used in connection with the guard rail and that the wedge plate can be brought into engagement with the base of the brace block instead of being brought directly into engagement with the base of the guard rail, if desired.

Although a preferred form of clip is shown in the accompanying drawings, it is obvious that other well known forms of spacing devices can be used so far as the operation and construction of the wedge plate is concerned and that in certain cases spacing means may be omitted.

It will also be obvious that various minor modifications may be made in the details of construction herein set forth which are within the skill of the mechanic without departing from the invention, provided the means set forth in the following claims be employed.

We claim as our invention:

1. In a rail tie plate clamp, the combination with a tie plate having a track rail and a guard rail thereon and provided with a solid abutment having a diagonal edge, of a clip holding the track rail and the guard rail comprising two parts movable with respect to each other, one of said parts being normally secured in fixed relation to the tie

plate and provided with means overlapping the top of the other part to hold same against vertical displacement, a wedge plate arranged between the base of the guard rail and said abutment, and means for holding the wedge plate in adjusted position. 70

2. In a rail tie plate clamp, the combination with a tie plate provided with a fixed abutment and having track rails and a spacing clip mounted thereon, said clip comprising two parts interlocking with the rails and with each other, one of said parts being loosely mounted with respect to the tie plate and the other part being provided with a flange overlapping the top of said part and interlocking therewith, of a wedge plate engaging the base of one of said rails to force said clip parts together and hold the same in interlocking position, and means for holding the wedge plate in adjusted position 80 with relation to the tie plate. 85

3. In a rail tie plate clamp, the combination with a tie plate provided with a fixed abutment and having track rails and a spacing clip mounted thereon, said clip comprising two parts, each interlocking with one of the track rails, one of said parts being loosely mounted on the tie plate and having a recess formed therein and the other part being adjustably secured to the tie plate and having a projection engaging in said recess, of a wedge plate engaging said abutment and the base of one of the track rails to hold said clip parts in interlocking position and a washer interlocking with the wedge plate to 100 hold the same in adjusted position. 90

4. In a rail tie plate clamp, the combination with a tie plate provided with a fixed abutment and having track rails and a spacing clip mounted thereon, said clip comprising two parts, one of said parts being secured to the tie plate and being provided with a flange overlapping the top of the other part, said other part being held against vertical displacement by the fixed 105 part and held against lateral displacement by the guard rail, of wedging means engaging the said abutment and the base of one of said rails to hold said rails and clip parts in adjusted position with relation to the tie 110 plate. 115

5. In a rail tie plate clamp, the combination with a tie plate and a track rail movably mounted thereon, of a wedge plate mounted on the tie plate between the track 120 rail and a fixed abutment, said plate being provided with a diagonally arranged slot and having a portion of its upper surface provided with locking teeth, a bolt projecting through said slot and provided with a 125 non-circular head, a bearing for said head permitting rocking movement thereof in the bearing, and a washer mounted on said bolt and having a portion of its bottom provided with locking teeth adapted to engage the cor- 130

responding surface of the wedge plate, and means for forcing the locking teeth on said plate and washer into wedging engagement.

6. In a rail tie plate clamp, the combination with a tie plate and a track rail movably mounted thereon, of a wedge plate mounted on the tie plate between the track rail and a fixed abutment, said plate having a portion of its upper surface roughened, a washer 10 having a roughened surface adapted to engage the corresponding surface on the wedge plate and means for holding the wedge plate and washer in adjusted position, said holding means being secured to the tie plate and 15 having limited rocking movement in one direction with respect thereto to permit accurate fitting of the washer without disturbing the wedge plate.

7. In a rail tie plate clamp, the combination with a tie plate provided with a fixed guiding abutment, and a track rail movably mounted on said tie plate, of a wedge plate arranged between said track rail and abutment and having a portion of its upper surface 25 face provided with teeth, of a locking washer having a portion of its bottom surface provided with teeth to engage the corresponding surface on the wedge plate and means for securing the washer whereby it can be 30 fitted in any adjusted position of the wedge

plate and normally exert a pull on the same in the direction of wedging movement of the wedge plate.

8. In a rail tie plate clamp, the combination with a tie plate provided with integral 35 fixed abutments adjacent the opposite ends thereof, one of said abutments being provided with a diagonal face, a main rail and a guard rail loosely mounted on said tie plate, a clip between said rails comprising 40 two parts interlocking with said rails and with each other, one of said parts being fixed with relation to the tie plate and the other part being loosely mounted thereon, a wedge plate seating on said tie plate between the 45 diagonal abutment and one of the track rails, said plate having a toothed upper surface, a locking washer having a corresponding toothed surface interlocking with the wedge plate, and a bolt having a tilting 50 movement in one direction securing said washer in wedging engagement with said plate.

This specification signed and witnessed this 16 day of April A. D., 1914.
